UNITED STATES PATENT OFFICE.

ARTHUR G. HENRICKS, OF MILWAUKEE, WISCONSIN, ASSIGNOR TO PAWLING & HARNISCHFEGER COMPANY, OF MILWAUKEE, WISCONSIN, A CORPORATION OF WISCONSIN.

CONTACT FINGER.

Application filed March 18, 1921. Serial No. 453,352.

To all whom it may concern:

Be it known that I, ARTHUR G. HENRICKS, a citizen of the United States, residing at Milwaukee, county of Milwaukee, and State 5 of Wisconsin, have invented new and useful Improvements in Contact Fingers, of which the following is a specification.

This invention relates to electrical switches and is particularly directed to the 10 relatively stationary contacts of such switches, for instance, the contact fingers of controllers.

The primary object of this invention is to provide a pivoted contact finger which is 15 so constructed that the finger bar may be readily removed by manipulating easily accessible parts upon its outer side without disturbing the pivoted portion, and to so organize such mounting that for the purpose 20 of such removal, transverse movements of the finger or of parts of the mounting are not necessitated whereby either an open or closed pivotal bearing may be used.

Other objects are to provide a contact, 25 such for example, as the contact finger of controllers, which tho resiliently pressed, will nevertheless be retained in substantially correct position altho the resilient means may break; to provide a contact 30 finger which will insure good contact and avoid stubbing or binding; which may be cheaply and readily manufactured and applied to existing types of controllers and which altho readily removable and accessible 35 and capable of heavy duty, nevertheless will have relatively small transverse dimensions so that a series of such contacts may be arranged upon a supporting insulating base with relatively small spacing therebetween. 40

For the purpose of illustrating an embodiment of the invention, a contact finger for a drum controller has been shown in the drawings, in which:

Fig. 1 is a side elevation of a contact finger partly in section showing in dotted lines the contour of the co-operating controller drum.

Fig. 2 is a section on the line 2—2 of 45 Fig. 1 with the insulating base removed.

The contact finger comprises a bar or body portion 1 which may be formed of sheet brass with the longitudinal edges up-

turned to give the requisite stiffness by providing a substantially channel section. This 55 body portion carries at its outer end a contact proper 2 which is adapted to make sliding contact with the movable contacts carried upon the controller drum indicated at 3.

A supporting portion is provided which may be of copper and is formed with upturned ears 4 which carry a pintle 5, such pintle being conveniently retained in position by split pins 6. Pivotaly mounted 60 upon the pintle is a block 7 of metal which is rectangular in outline and has a widened lower portion 8 which loosely engages the inner surfaces of the upturned ears 4 of the support. This block passes thru a rectangular opening formed in the bottom portion 9 of the contact finger and extends a slight distance thereabove and is provided with a hole 10 whose lower surface is substantially in line with the upper surface of 70 the bottom portion 9 of the contact finger when in normal position. A pin 11 is passed thru this hole and serves to retain the contact finger upon the block 9, such pin having an upturned substantially right 75 angle portion 12 which forms a convenient manipulating handle.

To provide additional bearing contact between the body portion and the block 7, such body portion may have downwardly turned 85 flanges adjacent the sides of the opening thru which the block passes. The support has an upwardly extending forward arm 13 which is provided with an outwardly projecting portion 14. The rear portion of the support has a downwardly extending portion 15 to which an electrical lead 16 is secured by means of a screw 17. The support is conveniently held in position upon an insulating base 18 by means of screws 19 and 20 95 which pass thru tapped holes in the bottom portion of such support, the screw 19 extending upwardly a slight distance above such support as indicated at 21.

The contact finger is placed in intimate 100 electrical contact with the lead 16 by means of a relatively large, flexible, braided conductor 22 which has at one end a terminal 23 secured beneath the screw 17 and in engagement with the lead 16, and at its other 105 end a terminal 23 which is riveted to the rear

end of the contact finger, such rivet forming an enlarged projection 24 extending a slight distance below the under side of the contact finger. A spring 25 is positioned between

5 the rear end of the contact finger and the support and is retained in position by means of the projecting end 21 of the screw 19 and the projecting portion 24 of the rivet.

To prevent excessive inward motion of 10 the contact an adjusting screw 26 is threaded thru the contact finger and engages the top or projection 14 of the support. The upper end of the screw is provided with a square head 27 which co-operates with the upturned 15 lip 28 of a spring 29 to prevent accidental rotation of the screw.

The positioning of the pin 11 with its right angle arm 12 in close proximity to the terminal portion 24 allows such pin and terminal to co-operate to prevent accidental withdrawal of the pin, for when the pin is slid rearwardly the base of the right angle portion 12 engages the terminal 24 and prevents further movement of such pin. However, when it is desired to remove the pin, 25 the rear portion of the contact finger is depressed against the action of the spring 25 and the pin is then withdrawn, passing over the terminal portion 24 of the conductor. 30 The contact finger may then be slipped outwardly from off the rectangular member 7.

It will thus be seen that a contact finger has been provided which may be quickly and readily removed by the manipulation of means which are readily accessible from the outer side of the contact finger. It will also be seen that inadvertent or accidental disengagement of the contact finger and support is prevented and such finger is securely 40 retained in operative position except when such detachment is voluntarily made.

Stubbing or binding is avoided by having the under surface of the contact 2 and the pivot 5 substantially in line with a tangent 45 from the upper surface of the controller drum, so that the contact may readily ride over the co-operating segments of the drum, it being understood that the usual beveled or rounded faces of the contact 2 are provided.

It will also be seen that these contact fingers may be placed in close proximity to each other when it is desired to closely assemble a series of fingers upon a controller 55 for instance, and that the removal of any one finger does not necessitate a lateral motion of any of the connecting members thereby minimizing the necessary lateral clearance. Also, if the spring should break, the finger 60 is still prevented from damaging other portions of the controller as it is so retained that it is prevented from either falling off or being knocked off its support and also prevented from having sidewise swinging 65 motion by the rectangular contour of the

member 7 together with the corresponding co-operating rectangular opening in the contact finger.

I claim:

1. In an electric switch having movable and stationary contacts, the combination of a contact finger having a body portion, a contact carried at one end thereof, a spring resiliently bearing upon the other end thereof, and intermediate pivotally mounted means detachably joined to said contact finger, and adapted to be disconnected from the exterior side to allow the finger to be removed without disturbing the pivotal connection. 70

2. A contact finger comprising a body portion, a contact carried at one end thereof, a support, a member pivotally mounted upon said support and having slip joint connection on the exterior side with said contact finger, and a spring positioned between said support and said contact finger. 85

3. In a device of the character described, the combination of a support, an intermediate member pivotally connected with said support, a contact finger provided with an aperture receiving a portion of said intermediate member, and a slidable key on the exterior side of said contact finger positively connecting said intermediate member and said contact finger. 90

4. A contact finger comprising a body portion, a support, a member having pivotal connection with said support and extending thru said body portion, an exteriorly accessible pin for detachably securing said member to said body portion, and a spring positioned between said body portion and said support. 100

5. The combination with a support and connecting member pivoted to the support, a contact finger adapted to be loosely engaged by the connecting member, and a quick detachable connection between said member and the finger, adapted to be manually manipulated from the exterior. 110

6. The combination with a support, of a connecting member having closed pivotal connection with the support, a contact finger having an aperture through which the connecting member passes, a quick detachable member adapted to engage the connecting member and contact finger to normally prevent disengagement of the finger from the connecting member, and means for subjecting said quick detachable member to resilient pressure to prevent accidental disengagement thereof. 115

7. A contact finger comprising a body portion, a support mounted below said body portion, a member pivotally secured to said support and projecting into said body portion, and means upon the outer side of said body portion for detachably joining said body portion to said member. 125

8. A contact finger comprising a body portion, a contact positioned at one end thereof, resilient means acting upon the other end thereof, a support mounted adjacent said body portion, a member passing thru said body portion and pivotally joined to said support, a pin passing thru said member and engaging the upper face of said body portion, and a conductor electrically connecting said support and the last mentioned end of said body portion and having a terminal portion positioned adjacent one end of said pin whereby said pin is normally held in position by said terminal. 30
9. A contact finger comprising a body portion, a support therefor, means including a pin for retaining said contact finger in operative engagement with said support, 35 and a flexible conductor electrically joining said body portion and said support and having a terminal co-operating with said pin to retain said pin in operative position. 40
10. A contact finger comprising a support, a member pivotally mounted thereon, a body portion having at its forward end a contact, and provided with an opening thru which said pivotally mounted member passes, a pin passing thru said pivotally mounted member and retaining said body portion in engagement with a spring positioned between the rear end of said contact finger and said support, a flexible conductor electrically joining said support and the rear end of said contact finger and having a terminal portion co-operating with said pin to retain said pin in operative position, and a securing means passing thru said terminal and the rear end of said contact finger and engaging said spring to retain said spring in position. 45
11. In an electrical switch, the combination of an insulating base, a support mounted thereon, a screw passing thru said insulating base and support and retaining said support upon said base, said screw projecting above the upper surface of said base, a contact finger pivotally mounted upon said support, a conductor electrically joining said support and said finger, a rivet securing said conductor to said finger and having a portion projecting below said finger, and a spring positioned between said support and said finger and retained in position by said screw and said rivet. 50
